(57) **CLAIM**

We claim the ornamental design for a spine region of a binder, as shown and described.

DESCRIPTION

FIG. 1 is a front perspective view of a spine region of a binder embodying our new design, with the binder in a closed configuration.

FIG. 2 is a back perspective view of the spine region of FIG. 1.

FIG. 3 is a front elevational view of the spine region of FIG. 1.

FIG. 4 is a back elevational view of the spine region of FIG. 1.

FIG. 5 is a top-edge plan view of the spine region of FIG. 1. FIG. 6 is a bottom-edge plan view of the spine region of FIG. 1.

FIG. 7 is a left-side elevational view of the spine region of FIG. 1.

FIG. 8 is a right-side elevational view of the spine region of FIG. 1; and,

FIG. 9 is an elevational view of the outside surface of the spine region of FIG. 1, with the binder in an open configuration.

The dashed lines in the figures are for purposes of illustrating environmental structure that forms no part of the claimed design.
